CONDENSER APPARATUS

Joseph P. Lidiak, Lansdowne, Pa., assignor to
Westinghouse Electric & Manufacturing Com-
pany, East Pittsburgh, Pa., a corporation of
Pennsylvania

Application May 18, 1938, Serial No. 208,524

1 Claim. (Cl. 257—43)

This invention relates to surface condensers and more particularly to circulating systems therefor, and it has for an object the provision of a novel arrangement of inlet and discharge openings and valves therefor to provide for reversal of flow of circulating water through the condenser.

Another object of the invention is the provision of means, operable during operation of the condenser, to reverse the flow of water therethrough, to provide for removal of foreign matter therein.

These and other objects are effected by my invention as will be apparent from the following description and claim, taken in connection with the accompanying drawing, forming a part of this application, in which:

Fig. 1 is a diagrammatic elevational view of a condenser embodying the invention;

Fig. 2 is a transverse sectional view taken on the line II—II of Fig. 1, looking in the direction of the arrows;

Fig. 3 is a transverse sectional view taken on the line III—III of Fig. 2, looking in the direction of the arrows; and,

Fig. 4 is a transverse sectional view similar to Fig. 2, but showing the invention applied to an alternative condenser construction.

In certain condenser installations, it may frequently be necessary to clean the path of the cooling water to remove leaves or other foreign matter which has been carried into the apparatus by the water, whose source may be a river, lake, or the like. Such foreign matter, which collects against and covers the ends of the tube, can, to a considerable degree, be washed off by reversing the direction of flow of the water through the condenser. Such reversal of flow may be effected by the means hereinafter disclosed, without interruption of the operation of the condenser.

In the drawing, there is shown, at 10, a condenser comprised by a shell 11, having an exhaust steam inlet 12 at the top thereof, tube plates 13 at each end of the shell, water boxes 14 and 15 adjacent the tube plates 13, and a plurality of tubes 13a extending longitudinally of the shell and having their terminal portions mounted in the tube plates.

In the construction herein shown, the condenser is of the two-pass type, and the water box 14 is provided with a longitudinally extending partition 16 separating the interior into inlet and outlet chambers 17 and 18, respectively. The water box is provided with an inlet 19 and an outlet 21, and flow of water therethrough is con-

trolled by the novel valve means 22, hereinafter described.

The inlet 19 and outlet 21 are provided with radially extending flanges 23 having at the outer edges of their outer faces rabbets 24, providing annular recesses 26, in which are received valve disk members 27. A supply pipe 28 and discharge pipe 29, having elbows 31, are provided with flanges 32 abutting the rabbets 24, and secured thereto in any suitable manner, as by bolting. 10

As shown in Fig. 3, the valve discs 27 are provided with ports 33, of semi-circular configuration, and so disposed as to provide annular rims 34 to be received in the recesses 26 of the flanges 23. 15

The inlet 19 and outlet 21 are so disposed in the periphery of the water box that they overlie concentrically the edges of the partition 16, whereby they communicate with both the inlet chamber 17 and the outlet chamber 18, thus providing separate inlet passages 36 and 37 and separate outlet passages 38 and 39, the passages 36 and 38 communicating with the outlet chamber and the passages 37 and 39 communicating with the inlet chamber. 20

With the valve members 27 in the position shown, flow of water is permitted only through the inlet passage 37 to the inlet chamber, through the tubes 13a to the water box 15 at the other end of the condenser, thence back through the remaining tubes to the outlet chamber 18, and finally through the passage 38 to the discharge pipe 29. 25

The flow of water through the condenser is reversed simply by rotating each of the valves 180°. 35 This results in closing the passages 37 and 38 and opening 36 and 39, allowing entry of water to the outlet chamber 18 from whence it will flow through the tubes to the water box 15 and back to the inlet chamber 17, where it will leave the condenser through the passage 39 and the discharge pipe 29. 40

Means are provided for rotating the valve discs 27, and comprise shafts 41 extending axially of the valve discs, with the free ends extending 45 through and beyond the walls of the elbows 31. To prevent leakage at the point of passage through the walls of the elbows, stuffing boxes 42 are provided, having packing 43 retained therein by caps 44. Handwheels 46 are provided on the 50 valve shafts to aid rotation.

Preferably, vanes 47 are provided in the elbows 31 midway of the walls thereof, to direct the flow of water to the opened passages and reduce turbulence in the elbows. 55

In Fig. 4, there is shown the application of the same valve arrangement to a condenser construction of the type disclosed in my prior Patent No. 1,781,024, granted November 11, 1930. 5 This condenser differs from that described above solely in the provision of a baffle 48 providing outlet passage 49 and ensuring complete flooding of all of the tubes of the condenser.

While I have shown my invention in several 10 forms, it will be obvious to those skilled in the art that it is not so limited, but is susceptible of various other changes and modifications without departing from the spirit thereof, and I desire, therefore, that only such limitations shall be 15 placed thereupon as are imposed by the prior art or as are specifically set forth in the appended claim.

What I claim is:

A surface condenser comprising a shell having 20 an exhaust steam inlet and a condensate outlet; a waterbox at each end of the shell; tube plates separating the waterboxes from the interior of the shell; a plurality of tubes extending longitudinally of the shell from end to end thereof with 25 their ends mounted in the tube plates; one of said waterboxes constituting a reversing chamber; a partition extending longitudinally of the other water box dividing it into first and second chambers, said waterbox having an inlet and an

outlet in its side walls overlying the side edges of said partition and communicating with both chambers of said waterbox; annular flanges defining the exterior of the inlet and of the outlet and being rabbed to provide radially inward 5 facing recesses in the outer faces thereof; a disc-like valve member rotatably received in each recess with its inner face adjacent the edge of the partition and having a semi-circular opening therethrough; supply and discharge pipes having 10 flanges at one end overlying the flanges of the inlet and outlet, respectively, and preventing displacement of the valve members from their recesses; and means extending exteriorly of the pipes and condenser for rotating said valve members, whereby in one position of the valves the supply and discharge pipes communicate only 15 with said first and second chambers, respectively, for normal flow of water from said first chamber through some of the tubes to the reversing chamber and then back through the remaining tubes to said second chamber, and in another position of the valves the supply and discharge pipes communicate only with the second and first chambers, respectively, to effect reversal of the water 20 circulation through the condenser to cause removal of foreign matter collected in said condenser during normal operation thereof.

JOSEPH P. LIDIAK.
